PIANO CASE

Winsor D. White, Jr., Blowing Rock, N.C., assignor to D. H. Baldwin Company, Cincinnati, Ohio, a corporation of Ohio

Filed Feb. 9, 1965, Ser. No. 83,756

Term of patent 14 years

(Cl. D56—9)

The figure is a perspective view of a piano case embodying my new design.

The side of the piano case, not shown, is the same as the side shown.

The back, not shown, is conventional, and the conventional keyboard fragmentarily shown by means of solid lines is continuous across the piano as indicated by the long dash dot lines.

I claim:

The ornamental design for a piano case, substantially as shown and described.
